UNITED STATES PATENT OFFICE.

ARCHIBALD FINDLAY MCKENZIE, OF WHYTEWOLD, MANITOBA, CANADA.

SAW-VISE.

1,266,135.

Specification of Letters Patent.

Patented May 14, 1918.

Application filed May 17, 1917. Serial No. 169,291.

To all whom it may concern:

Be it known that I, ARCHIBALD FINDLAY MCKENZIE, of the village of Whytewold, in the Province of Manitoba, Canada, have invented certain new and useful Improvements in Saw-Vises, of which the following is the specification.

The invention relates to a vise particularly adapted for holding saw blades during the 10 sharpening operation and the object of the invention is to provide an inexpensive, simply constructed, easily set up and operated vise for positively holding the saw blade in position.

With the above object in view the invention consists essentially in a pair of stationary base plates, a pair of plates slidably mounted on the base plates and provided with extending brackets, a clamping jaw extending between the brackets and adjusting levers for manipulating the sliding plates, the parts being arranged and constructed as hereinafter more particularly described and later pointed out in the appended claim, 25 reference being had to the accompanying drawing in which:—

Figure 1 represents a plan view of my vise as it appears mounted on a bench.

Fig. 2 represents a vertical sectional view 30 through the upper corner of the bench in a location between the brackets.

Fig. 3 represents a plan view of one of the base plates.

Fig. 4 represents a front end view of the 35 base plate.

Fig. 5 represents a side view of the lever.

Fig. 6 represents a plan view of one of the sliding plates.

In the drawing like characters of reference indicate corresponding parts in the several figures.

1 represents a work bench to the forward side of which I fasten preferably a lengthwise extending wood strip 2 which has the 45 upper edge thereof continuous with the upper face of the bench.

To the top face of the bench I secure permanently a pair of base plates 3 and 4 which are spaced a suitable interval apart depending on the length which the vise is made. Each base plate is substantially rectangular in form and is fastened to the bench by a screw 5 and it is supplied on the top side 50 with an integral upstanding cross strap 6 which provides an opening 7 and forms a guide for a part later described. The strap

is fitted centrally with an elongated vertically disposed opening 8. 9 and 10 represent a pair of sliding plates mounted on the top faces of the base plates and passed 60 through the openings 7 beneath the straps, the said straps operating to guide the plates when moved inwardly or outwardly. The inner ends of the sliding plates are slotted as indicated at 11 to allow of convenient access to the screw and the outer ends of the plates are provided with integral extending more or less V-shaped brackets 12 and 13 which have their ends terminating in horizontally opposing heads 14 disposed opposite the outer face of the strip 2. The bracket heads are connected by a lengthwise extending jaw 15 which has the inner face thereof contained in the vertical plane and directly opposing the outer face of the 75 strip 2.

Each of the sliding plates is provided in a location beneath the straps with a comparatively large circular centrally located vertically disposed opening 16 which lies in 80 each instance above a smaller circular opening 17 provided in each of the base plates. 18 and 19 represent vertically disposed operating pins passed into and through the openings 8, 16 and 17 and fitted each at the 85 opening 16 with a horizontally disposed inwardly extending lug 20 which is of a length such that the tip of the lug touches one edge of the opening when the front side of the pin is against the diametrically opposing 90 edge of the opening.

The lower ends of the pins are enlarged to prevent the withdrawal of the pins upwardly, while the upper ends are fixed in the ends of operating levers 21 and 22. The 95 arrangement of the levers in respect to the lugs is such that when the levers are in the position shown in Fig. 1 of the drawing, the lugs point inwardly. This position of the levers is the in or jamming position of the 100 jaw, while if they are both swung in the direction of the arrows the jaw is released.

It is here explained that as the lever is turned in the direction of the arrows the lugs travel in the openings 16 and in so doing effect the shifting of the sliding plates in a direction away from the bench and consequently cause the jaw to release from the strip.

When the device is to be used the levers 110 are first swung to release position and the saw blade as indicated at 23 is inserted be-

2
tween the jaw and the strip. The levers are then swung in and the saw is jammed in position.

In this action it is to be noted that when 5 the levers are swung back the jaw is positively locked as the lugs reach a dead center position behind the pins.

What I claim as my invention is:—

In a saw vise a base plate provided with 10 an upstanding cross strap, a sliding plate mounted on the top face of the base plate and passing beneath the strap, a substantially inverted V-shaped bracket extending

from one end of the sliding plate, a pin carried by the base plate and strap and extending through the sliding plate, a lug on the pin and operating within a circular opening provided in the sliding plate and a lever attached to the pin. 15

Signed at Whytewold, this first day of 20 May, 1917.

ARCHIBALD FINDLAY MCKENZIE.
